(57) **CLAIM**

The ornamental design for a notebook computer, as shown and described.

DESCRIPTION

FIG. 1 is a top front perspective view of a notebook computer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is another top view thereof showing an unfolded state of the notebook computer.

The broken lines illustrating portions of the notebook computer form no part of the claimed design. The portions between the solid line perimeter edges and the broken lines in FIG. 9 form no part of the claimed design.

1 Claim, 5 Drawing Sheets
